UNITED STATES PATENT OFFICE.

FREDERICK HAYTHORN, OF PHILADELPHIA, PENNSYLVANIA.

IMPROVEMENT IN SPINNING-FRAMES.

Specification forming part of Letters Patent No. 78 085, dated May 19, 1868.

To all whom it may concern:

Be it known that I, FREDERICK HAYTHORN, of Philadelphia, in the county of Philadelphia and State of Pennsylvania, have invented a new and useful Improvement in Spinning-Frames; and I do hereby declare that the following is a full, clear, and exact description thereof, which will enable those skilled in the art to make and use the same, reference being had to the accompanying drawings, forming part of this specification.

The nature of my invention relates to an improvement in spinning-frames; and it consists in providing a ring-spinning frame with a series of pivoted guards, these being on guard between the adjacent spindles to prevent the yarn of each bobbin or cop from coming into contact with that of the adjacent bobbins or cops on either side during the act of being spun. To this end I have arranged upon the side of the ring-rail an oscillating shaft provided with fingers, which support the said guards in a vertical position between each of the spindles in such a manner that the said shaft may be swung out of the way while doffing the cops or bobbins.

To enable others skilled in the art to make and use my invention, I will proceed more fully to describe its construction and operation, reference being had to the accompanying drawings, and to the letters and figures of reference marked thereon.

Figure 1 is a plan view of a portion of a ring-rail with my improvement attached. Fig. 2 is a section on the line $x x$ of Fig. 1. Fig. 3 is a section on the line $y y$ of Fig. 1, and Fig. 4 is a section on the line $x y z$ of Fig. 3.

Similar letters of reference indicate corresponding parts.

A in the drawings represents a portion of a ring-rail as ordinarily constructed.

B represents a series of brackets on one side of the same, in which is arranged the shaft C

supporting the fingers. D are the fingers, and E the guards. The said brackets are secured to the ring-rail by set-screws so placed that they may also serve to secure the rings in place. The said shaft may be turned on its axis to move the guards out of the way while doffing the bobbins or cops.

All the parts of my improvement may be made of iron, wood, or any other material. I prefer, however, to make the guards of tin or sheet-iron and the other parts of iron. The fingers, besides serving as supports for the guards by their contiguity to the rings, also serve to clear the travelers from kinks or snarls, which are often the cause of breakages, thus saving labor and waste in piecing or mending the broken yarn. The said guards are secured to the fingers by passing the lower end through a tapered slot in the latter, of the right size to agree with the tapered end of the guard, the projecting portion being turned under the lower side of the finger, as clearly shown in Figs. 3 and 4; but I do not desire to limit myself to this manner of securing them, as many other obvious plans may be adopted with equal advantage. I have found in practice these guards to serve a very useful and advantageous purpose of preventing the yarns of each bobbin or cop from coming into contact with those of the adjacent bobbins or cops while it is performing the circular movement given to it by the twisting operation during its passage from the guide-eyes to the traveler.

Having thus fully described my improvements, what I claim, and desire to secure by Letters Patent, is—

The guards E, in combination with the fingers D and shaft C, substantially as described, for the purpose specified.

FREDCK. HAYTHORN.
